Claims priority, application Netherlands Feb. 23, 1959
2 Claims. (Cl. 259—98)

This invention relates to a homogenizer meant for comminuting the particles in an emulsion, e.g., the fat globules in milk, and comprising a homogenizing member comprising a seat having a bore therein and a follower cooperating with said seat, which follower is kept urged against said seat under a controllable pressure, the pressure exerted by the liquid to be homogenized forming a narrow slit between the seat and the follower for the passage therethrough of the emulsion to be homogenized.

In the conventional homogenizers of the type in question the follower is mechanically kept urged against the seat by an adjustable force exerted by a spring or a weight. The construction used for homogenizers of this type has various disadvantages, the main disadvantages being the great wear and tear of essential parts, the difficult and time-consuming removal and/or replacement of the follower, which is periodically necessary. Moreover the pressure by means of which the follower is kept urged against the seat by an adjustable spring is difficult to control and therefore unreliable.

The object of this invention is to avoid said disadvantages by an improved construction of a homogenizer of this type.

To achieve this end according to the invention the homogenizer is characterized in that the follower is coupled with the piston of a hydraulic cylinder provided with an adjustable throttling means. According to another feature of the invention the coupling between the follower and the piston of the hydraulic cylinder may consist of a coupling member adapted to be interposed between said piston and said follower and to be removed in opposition to a weak spring acting on said piston.

According to a further feature of the invention the follower may be so connected via the coupling and the piston with the mechanism driving the pressure plunger(s) of the homogenizer that said follower is stepwise rotated about its axis.

By applying the invention a homogenizer is obtained in which the pressure with which the follower is kept urged against its seat admits of being accurately adjusted in a simple manner. Furthermore the coupling member and thus the follower and the seat may be removed very easily. By the measure of rotating the follower stepwise the abutting surfaces of the follower and the seat are kept trued relative to each other, so that it is only seldom necessary to true the follower and the seat.

An embodiment of the homogenizer will be described hereinafter for elucidating the invention, reference being made to the accompanying drawing, in which:

FIGURE 1 is a vertical longitudinal section of the homogenizer;

FIGURE 2 is a showing in perspective of the homogenizing member (partly cut away);

FIGURE 3 is a showing in perspective of the driving mechanism of the press pumps belonging to the homogenizer.

According to the drawing the homogenizer comprises a frame 1 provided with a number of pump chambers 2, each having a suction valve 3, a delivery valve 4 and a plunger 5 of its own, all of said chambers being connected to a common supply conduit 6 for the emulsion to be homogenized. The pressure plungers 5 are each

2

driven by an eccentric connecting rod mechanism 7 driven by a common driving shaft 8.

The pumping chambers 2 discharge into a common pressure chamber 9, in which the homogenizing member is mounted. Said homogenizing member comprises a stationary bored seat 10 connected to a discharge conduit 11 and a follower 12 which is axially and rotatably journaled in the frame 1. The abutting ends of the seat 10 and the follower 12 have a reduced external diameter so that oppositely directed thrust faces 13 and 14 are formed in such a manner that when a predetermined pressure in the pressure chamber 9 is reached the follower 12 will axially move away from the seat so that a narrow slit will form between the seat and the follower, through which slit the emulsion will be forced under a very high pressure and at a very high speed and it is this feature on which the homogenizing action of the homogenizer is based.

The pressure in the pressure chamber 9 at which the slit between the seat 10 and the follower 12 will form depends on the pressure by means of which the follower 12 is kept urged against the seat 10. Pressure is applied to the follower 12 by a piston 16 which is mounted in a hydraulic cylinder 17. The piston 16 is coupled to follower 12 by a removable coupling member 15 which is non-rotatably coupled to both the piston 16 and the follower 12. The hydraulic cylinder 17 which contains a weak compression spring 18 in order to keep the follower 12 urged against the seat with a slight force via the piston 16 and the coupling member 15, is connected to a pump 20 by a conduit 19, said pump being fed from an oil bath 21. Furthermore, a pressure gauge 22 and a throttling member 23 are connected to the cylinder 17, said throttling member discharging in the oil bath 21, the oil thus discharged being at the same time utilized for lubricating the driving mechanism 7, 8.

Because the throttling member 23 admits of being accurately adjusted it is possible in view of the specific ratio between the operative areas of the piston 16 and the thrust face 13 of the follower 12 to exactly ascertain by reading the pressure gauge 22 at what pressure in the pressure chamber 9 the slit between the seat 10 and the follower 12 will open. The pressure on said pressure gauge, therefore, has a fixed relationship to the pressure in the chamber 9, so that it is not necessary to connect a pressure gauge to said pressure chamber 9, which makes for a more hygienic operation of the homogenizer.

By providing the piston 16 with a rod 24 which via a pawl and ratchet gear 25 is rotated stepwise by an arm 26 which has its one end carrying a roller kept into contact with one of the connecting rods 7, the follower 12 is kept rotating in order to make it wear evenly.

When the homogenizer is inoperative it is sufficient for removing the follower 12 to axially move the coupling member 15 in opposition to the spring 18 and to subsequently remove said member, whereupon the follower 12 becomes accessible while also the seat 10 may be removed.

It will be clear that the principle according to the invention admits of structural variants of the embodiment described. More particularly it is possible to so construct the homogenizer that the direction of flow through the slit in the homogenizing member is directed radially outwards instead of radially inwards.

I claim:

1. An emulsion homogenizer comprising a casing having a homogenizing chamber therein, an annular homogenizing member having a seat on one end thereof and being stationarily mounted in said chamber, said casing having an outlet opening therein through which said annular homogenizing member opens, a follower slidably in said casing in alignment with said homogenizing member and bearing against said seat, said follower being mov-

able away from said seat under liquid pressure in said chamber exerted on said follower, a counter pressure exerting means mounted on said casing in spaced relationship thereto and including an axially movable pressure transmitting member, a removable coupling member between said pressure transmitting member and said follower, and weak spring means in said pressure exerting means urging said pressure transmitting member toward said coupling member with a force only sufficient to hold said follower on the seat of said homogenizing member when no liquid pressure in said chamber is exerted on said follower, whereby, when no hydraulic pressure is exerted on said pressure transmitting member, said coupling member can be removed by moving it against said spring means for separating it from said follower, and said follower can be slid out of said casing.

2. An emulsion homogenizer as claimed in claim 1 in which said coupling member is non-rotatably coupled

with said pressure transmitting member and said follower, and said pressure transmitting member has means attached thereto for rotating said pressure transmitting member, said coupling member and said follower periodically.
